(57) **CLAIM**

The ornamental design for an escutcheon plate for a safe, as shown and described.

DESCRIPTION

FIG. 1 is a front perspective view of an escutcheon plate for a safe, showing our new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

The portions of the drawings shown in broken lines form no part of the claimed design.

All surfaces not shown form no part of the claimed design.

1 Claim, 6 Drawing Sheets**FIG. 1**

FIG. 2

FIG. 3

FIG. 4

FIG. 5
